UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed March 30, 1918, Serial No. 225,774. Renewed April 14, 1922. Serial No. 552,595.

To all whom it may concern:

Be it known that I, MORRIS P. HOLMES, a citizen of the United States, residing at Claremont, in the county of Sullivan and State of New Hampshire, have invented certain new and useful Improvements in Mining Machines, of which the following is a full, clear, and exact specification.

My invention relates to mining machines. It has for its object to provide an improved feeding mechanism for such a machine. A further object is to provide an improved feeding mechanism especially adapted to use in connection with flexibly fed mining machines of the type slidably on a mine bottom. A still further object of the invention is to provide an improved feeding mechanism having provision whereby the machine may be fed in either direction at a slow or cutting speed or at any one of a plurality of different speeds, my invention including improved friction mechanism operatively connected in an improved manner to the feeding mechanism and controlled by improved controlling mechanism whereby these objects may be obtained. These and other objects and advantages of my improved construction will, however, hereinafter more fully appear.

In the accompanying drawings I have shown for purposes of illustration one embodiment which my invention may assume in practice.

In these drawings,—

Fig. 1 is a plan view, partly broken away, of a mining machine having my invention applied thereto.

Fig. 2 is an irregular transverse vertical section, taken substantially on the line 2—2, Fig. 1.

Fig. 3 is an irregular vertical section, taken substantially on the line 3—3, Fig. 1.

Fig. 4 is a detail vertical section, on an enlarged scale, of the reversible friction device.

Fig. 5 is a horizontal section on the line 5—5, Fig. 4.

Fig. 6 is a diagrammatic view illustrating the operation of a machine embodying the invention.

The invention is herein illustrated, as embodied in a mining machine of the familiar room and pillar type, said machine, as is usual in machines of this type, comprising

ing a body from the forward end of which projects a fixed cutter bar 10 (Figs. 1 and 6) carrying a cutter chain 11 provided with cutter bits 12. The machine body comprises a motor casing 13 and a gear or transmission casing 14, the walls of said casing 14, together with a suitable transverse horizontal partition 15 (Figs. 2 and 3) therein, constituting a framework which provides the necessary bearings, guides, and supports for the various parts of the feeding mechanism, except as hereinafter pointed out.

Within the motor casing 13 is an electric or other motor 16 (Fig. 1) which operates, through transmission mechanism hereinafter described, to actuate the cutter chain and the feeding means for the apparatus, said feeding means including a feed chain 17 secured at its ends to suitable jacks or other securing devices at opposite ends of the path of travel of the machine, as shown, for example, at A and B in Fig. 6. Said chain passes over suitable guide rollers or sprockets 18 on the machine body and is actuated by a feed sprocket 19 in the casing 14, said feed sprocket being actuated by transmission mechanism, hereinafter more fully described, from the motor 16. The parts thus far referred to, as to their general organization, arrangement, and function, are well known in the art, and, except as hereinafter pointed out, require no further description in detail.

Also, except as to certain important novel features hereinafter more fully described, the mechanism for actuating the cutter chain 11 from the motor 16, as also the transmission mechanism for operatively connecting said motor with the feed sprocket 19, may be of any usual or suitable form. As herein shown, the shaft 20 (Fig. 1) of the motor 16 has fast thereon a bevelled gear 21 which meshes with a bevelled gear 22 fast on an upright shaft 23 suitably journaled in the frame-work. Also fast on the shaft 23 is a pinion 24 which meshes with a gear 25 (Figs. 1 and 2) keyed or otherwise secured to a second shaft 26, suitably journaled in the framework, and which may be the usual friction shaft of the machine. The gear 25 is provided with a hub 27 on which is mounted a sprocket 28 for driving the cutter chain 11, said sprocket being adapted

2
to be clutched to said hub by means of a suitable clutch mechanism indicated by the numeral 29. Such clutch mechanism, being usual in machines of this type, is not 5 illustrated in detail herein.

Loosely mounted on the shaft 26 is a hub 30 adapted to be operatively connected with said shaft 26 for rotation thereby in either direction by a reversible friction device constituting an important feature of the present invention and hereinafter more fully described. The hub 30 is formed with a pinion 31 which meshes with a gear 32 (Figs. 2 and 3) rotatably mounted on a fixed vertical shaft 33 suitably supported in the framework. Slidably and rotatably mounted on the shaft 33 is a sleeve 34 having at its end a clutch face 35 adapted to engage a cooperating clutch face 36 on the gear 32. The sleeve 34 is formed with a toothed portion constituting a pinion 37 which meshes with a gear 38 (Fig. 3) keyed or otherwise fast upon the hub of the feed sprocket 19, which sprocket is rotatably mounted on an upright shaft 39 suitably fixed in the framework.

By the connections above described, the feed sprocket 19 is rotated to produce a relatively fast feed. In order to provide for a relatively slower feeding speed, the following transmission mechanism, operative alternatively with a portion of the mechanism last described, is herein shown.

The hub of the gear 32 is formed with a pinion portion 40 which meshes with a gear 41 (Figs. 1 and 2) rotatably mounted on a stud shaft 42, suitably supported in the framework. The gear 41 has a pinion portion 43 which meshes with a gear 44 (Figs. 1 and 3) fast on a sleeve 45 rotatably mounted on an upright shaft 46, also fixed in the framework. The end of the sleeve 45 has secured thereto a pinion 47 which meshes with a gear 48 rotatably mounted on the shaft 33.

The sleeve 34 is provided at its end opposite the clutch face 35 with a second clutch face 49 adapted to engage a cooperating clutch face 50 on the gear 48. By moving the sleeve 34 longitudinally to cause one or the other of the clutch faces 35 or 49 to engage the cooperating clutch faces 36 or 50, the pinion 37 on said sleeve, which pinion drives the feed sprocket 19 through the gear 38, may be rotated either at fast speed, directly by the gear 32, as above explained, or at slow speed from said gear 32 through the gearing 40, 41, 43, 44, 47, and 48.

In order that the clutch sleeve 34 may be conveniently shifted, said sleeve is formed with a circumferential groove which is engaged by a clutch fork 51 (Figs. 1 and 2) formed on a lever 52 (Fig. 1) pivoted at 53 to the framework. The lever 52 is provided with a slot which receives an eccen-

tric pin or stud 54 on a shaft 55 journaled in the framework and provided at its opposite end with a bevelled gear 56 which meshes with a bevelled gear segment 57 on a hand lever 58 rotatably mounted on a stud 59 projecting from the framework. By turning the lever 58 in one direction or the other, the clutch fork 51 is operated to connect the sleeve 34 with either the gear 32 or the gear 48.

As shown in Fig. 4, the reversible friction device above referred to for operatively connecting the hub 30 and shaft 26 is, in accordance with the present invention, preferably constructed and arranged substantially as follows: Keyed or otherwise secured to the shaft 26, is a sleeve 60 adapted to be alternatively clutched to the hub 30 or to an annulus 61, loosely surrounding said sleeve, by means of friction disk clutches 62 and 63, respectively. The clutches 62 and 63 are rendered alternatively operative to connect the hub 30 or the annulus 61 with the sleeve 60, by means of a clutch controller comprising a sleeve 64 slidably mounted on a sleeve or bushing 65 on the usual threaded upper end 66 of the shaft 26, said sleeve 64 having arms 67 which slide in longitudinal grooves in the sleeve 60 and carry at their lower end an annulus or ring 68 interposed between the clutches 62 and 63. Downward movement of the sleeve 64 and ring 68 renders operative the clutch 62 to connect the sleeve 60 with the hub 30, while upward movement of said sleeve and ring disengages the clutch 62 and renders operative the clutch 63 to connect the sleeve 60 with the annulus 61, the latter being held against longitudinal movement by an annular stationary gear casing 69 held against rotation by suitable stops 69'.

When the hub 30 is directly connected to the sleeve 60 by the clutch 62, it will be seen that the pinion 31 will be rotated by the shaft 26 and in the same direction. The annulus 61 carries a beveled gear 70 which meshes with a series of beveled gears 71 (Figs. 4 and 5) rotatably mounted on inwardly projecting studs 72 carried by the gear casing 69, said gears 71 meshing with a beveled gear 73 carried by or forming a part of the hub 30. When the annulus 61 is clutched to the sleeve 60, it will be seen that the hub 30 and pinion 31 will be rotated from the shaft 26 through the gears 70, 71, and 73, and in a direction opposite to the direction of rotation of said shaft.

For convenience in assembling the parts, the gear casing 69 is preferably formed of two telescoping shells 74 and 75, secured together by means of screw plugs 76 seated in registering threaded openings in the walls of said shells, said plugs being preferably formed integral with the studs 72, 130

whereby any of the gears 71 may be conveniently removed by removal of the corresponding plug 76.

For operating the clutch controlling sleeve 64, there is provided a sleeve 77 slidably mounted on the exterior of said sleeve 64, said sleeves 77 and 64 having, respectively, internal and external shoulders 78 and 79 which, when the parts are in the normal or neutral position shown in Figs. 2 and 4, register with one another. The outer end of the sleeve 77 is interiorly threaded to receive a bushing 80 which, when the parts are in neutral or normal position, registers with a nut 81 on the exteriorly threaded outer end of the sleeve 64. Engaging the bushing 80 and nut 81 is a washer 82, while engaging the shoulders 78 and 79 is a similar washer 83, and between said washers 82 and 83 is interposed a spring 84 located in a recess between the sleeves 64 and 77.

As will now be seen, downward movement of the sleeve 77 will cause, through the bushing 80 and washer 82, a compression of the spring 84, which will be communicated through the washer 83 and shoulder 79 to the sleeve 64, causing downward movement of said sleeve and of the clutch controlling annulus 68, thereby rendering operative the clutch 62 to connect the sleeve 60 and hub 30. Similarly, upward movement of the sleeve 77, acting through the shoulder 78 and washer 83, will compress the spring 84, the tension of which will be transmitted through the washer 82 and nut 81 to the sleeve 64, causing upward movement of said sleeve and of the clutch controlling annulus 68, thereby rendering operative the clutch 63 to connect the sleeve 60 and annulus 61. It will be seen that movement of the sleeve 77 in either direction is yieldingly transmitted to the sleeve 64 through the spring 84.

For moving the sleeve 77, there is provided a trunion ring 85 interposed between an annular flange 86 on the sleeve 77 and a nut 87 in threaded engagement with the exterior of said sleeve. The ring 85 is provided with trunnions 88 which are engaged by the forked end of a lever 89 (Figs. 1 and 2) pivoted at 90 to an upright 91 carried by the framework, which lever 89 may be the usual friction loading lever of the machine. Intermediate its ends, the lever 89 is provided with a slot 92 which receives an eccentric pin 93 on the end of a shaft 94 journaled in the framework and provided at its opposite end with a beveled gear 95 (Fig. 1) meshing with a beveled gear segment 96 (Figs. 1 and 3) carried by a lever 97 fulcrumed on the upper end of the shaft 39. By moving the lever 97 in one direction or the other, it will be seen that, through the connections described, the pinion 31 may be connected

with the shaft 26 for rotation in either direction, causing, through the transmission connections described, a rotation of the feed sprocket 19 in either direction.

While the reversibility of the feed sprocket 70 may be utilized in a number of ways in the operation of the machine, there is diagrammatically illustrated in Fig. 6 the use of the feed mechanism in the operation of sumping. The position of the machine at the beginning of the sumping cut is indicated in broken lines. The feed chain 17, being anchored at one end by the adjacent jack A, after passing about one or more of the guide sprockets 18, is passed in a counter-clockwise direction about the feed sprocket 19, the opposite end of said chain being connected at B. The cutter chain being now started, the feed sprocket 19 is caused to rotate in a counter-clockwise direction, thereby drawing in upon the feed chain 17 and causing the machine to move from the broken line position into the full line position, thereby producing the sumping cut. Thereafter, without disturbing the anchorage of the chain 17 at A or B the direction of rotation of the feed sprocket 19 is reversed, causing said sprocket to rotate in a clockwise direction to cause the machine to travel across the face and cut the same in the usual manner.

As a result of my improvement, it will be observed that it is made possible not only to obtain as heretofore described reverse feeds including a reverse slow feed and a reverse fast feed greatly facilitating and expediting the various steps in the cutting and moving operations, but, by reason of my improved construction, to provide an improved feeding mechanism of a type well adapted to meet the demands of service. Further, it will be noted that this improved feeding mechanism includes improved reversible friction mechanism comprising a plurality of friction devices so located relative to the other elements of the feeding mechanism as to produce an improved and effective reversible mechanism having in each feed a friction mechanism of increased capacity, while the whole friction mechanism is of such improved and simplified form as to be exceedingly compact and adapted to cooperate with its improved operating mechanism and supplemental controlling mechanism in various forms in various combinations.

As will be seen by those familiar with the art, the double or reversible friction device herein shown and described may be readily and directly substituted, without changing any of the other working parts, for the single friction device usually employed in mining machines of a well known type. A machine of this type includes a transmission shaft of substantially the form, location, and function of the shaft 26 herein shown,

which shaft carries at its upper end the usual "friction" adapted to be "loaded" by mechanism of which the lever 97 and connections herein shown constitute a representative example. It will therefore be seen that the reversible friction device per se, may be conveniently substituted for the regular "friction" in such a machine and operated by the regular "loading" mechanism, and when so substituted, said device not only performs the function of the friction device which it has replaced, but also constitutes reversing means for the feeding mechanism, the friction clutches 62 and 63 providing for a suitable yielding drive in either direction.

This friction device may therefore be produced as a separate article of manufacture for application to any existing mining machine of the type referred to in substitution for the regular "friction" thereof, said device, when so applied, converting the unidirectional feeding mechanism of such a machine into a reversible feeding mechanism, while preserving the yielding character of the drive, the same forming the subject matter of a divisional application, Ser. No. 605,501, filed Dec. 7, 1922. I do not, however, herein claim the friction device per se. In connection with the appended claims it is to be understood that in the use of such expressions as "a transmission shaft, a transmission member thereon," etc., I mean a shaft which transmits power and a member thereon whose function it is to transmit power received from the shaft to some other element, and that by such terms I do not intend to designate an arrangement in which a member on a shaft constitutes the driving member for the shaft.

In this application it is not my intention to claim broadly the multiple friction feeding mechanism, such subject matter being covered by the claims of my copending application Ser. No. 225,340 filed March 28, 1918, nor is it my intention herein to claim in its broadest phases feeding means including a pair of friction clutches respectively operating to effect rotation in opposite directions of a transmission member and controlling means for said clutches including a controlling member for selectively connecting said clutches, an operating member, and operative connections between said controlling and operating members including resilient means, this subject matter being claimed in my copending application Ser. No. 552,594, filed Mar. 30, 1918, which is issuing simultaneously with this present application.

While I have in this application specifically described one form which my invention may assume in practice, it will be understood that this form of the same is shown for purposes of illustration and that the invention

may be modified and embodied in other forms without departing from its spirit or the scope of the appended claims.

What I claim as new and desire to secure by Letters Patent is:

1. In a mining machine, feeding mechanism including a transmission shaft, a transmission member thereon, and means for operatively connecting said member and shaft for rotation in the same or opposite directions automatically operating to connect them for rotation at equal angular rates irrespective of whether the connection be for rotation both in the same direction or one opposite to the other. 75

2. In a mining machine, feeding mechanism including a transmission shaft, a transmission member thereon, and means for yieldingly connecting said member and shaft for rotation in the same or opposite directions automatically operating to connect them for rotation at equal angular rates 85 irrespective of whether the connection be for rotation both in the same direction or one opposite to the other. 90

3. In a mining machine, feeding mechanism including a transmission shaft, a transmission member thereon, and a plurality of friction clutches for respectively connecting said member and shaft for rotation in the same or opposite directions automatically operating to connect them for rotation at equal angular rates irrespective of whether the connection be for rotation both in the same direction or one opposite to the other. 95

4. In a mining machine, feeding mechanism including a transmission shaft, a transmission member thereon, means for operatively connecting said member and shaft for rotation in the same or opposite directions, automatically operating to connect them for rotation at equal angular rates irrespective of whether the connection be for rotation both in the same direction or one opposite to the other and supplementary reversing mechanism cooperating therewith. 105

5. In a mining machine, feeding mechanism including a transmission shaft, a transmission member thereon, means for operatively connecting said member and shaft for rotation in the same or opposite directions, automatically operative to connect them for rotation at equal angular rates irrespective of whether the connection be for rotation both in the same direction or one opposite to the other, and supplementary speed changing mechanism cooperating therewith. 115

6. In a mining machine, feeding mechanism including a transmission shaft, a transmission member thereon, means for operatively connecting said member and shaft for rotation in the same or opposite directions, automatically operating to connect 125 them for rotation at equal angular rates irrespective of whether the connection be for rotation both in the same direction or one opposite to the other. 130

- them for rotation at equal angular rates irrespective of whether the connection be for rotation both in the same direction or one opposite to the other, and supplementary reversing and speed changing mechanism co-operating therewith. 70
7. In a mining machine, including a motor, motor driven feeding mechanism including a transmission shaft, a transmission member thereon, means for operatively connecting said member and shaft for rotation in the same or opposite directions, and supplementary reversing mechanism cooperating therewith arranged beyond the same with reference to said motor and controlling the application of power therethrough. 75
8. In a mining machine, including a motor, motor driven feeding mechanism including a transmission shaft, a transmission member thereon, means for operatively connecting said member and shaft for rotation in the same or opposite directions, and supplementary speed changing mechanism co-operating therewith arranged beyond the same with reference to said motor and controlling the application of power transmitted therethrough. 80
9. In a mining machine, including a motor, motor driven feeding mechanism including a transmission shaft, a transmission member thereon, means for operatively connecting said member and shaft for rotation in the same or opposite directions, and supplementary reversing and speed changing mechanism cooperating therewith arranged beyond the same with reference to said motor and controlling the application of power transmitted therethrough. 85
10. In a mining machine, feeding mechanism including a transmission shaft, a transmission member thereon, and means including a plurality of alternatively operative coaxial friction disc clutches for operatively connecting said member and shaft for rotation through a yielding drive in the same or opposite directions. 90
11. In a mining machine, feeding mechanism including a transmission shaft, a transmission member thereon, means including a plurality of alternatively operative coaxial friction disc clutches for operatively connecting said member and shaft for rotation through a yielding drive in the same or opposite directions, and supplementary reversing mechanism cooperating therewith. 95
12. In a mining machine, feeding mechanism including a transmission shaft, a transmission member thereon, means including a plurality of alternatively operative coaxial friction disc clutches for operatively connecting said member and shaft for rotation through a yielding drive in the same or opposite directions, and supplementary speed changing mechanism cooperating therewith. 100
13. In a mining machine, feeding mechanism including a transmission shaft, a transmission member thereon, and means for operatively connecting said member and shaft for rotation in the same or opposite directions at equal angular rates including a plurality of friction clutches alternatively operative during driving in opposite directions, and yielding means controlling the operation of each clutch. 105
14. In a mining machine, feeding mechanism including a transmission shaft, a transmission member, and means for operatively connecting said member and shaft for rotation in the same or opposite directions at equal angular rates including a plurality of friction clutches alternatively operative during driving in opposite directions, and a single yielding means controlling the operation of both clutches. 110
15. In a mining machine, feeding mechanism including a transmission shaft, a transmission member thereon, a plurality of friction clutches for respectively connecting said member and shaft for rotation in the same or opposite directions at equal angular rates, a sleeve movable longitudinally of said shaft, and an annulus carried by said sleeve for rendering said clutches alternatively operative. 115
16. In a mining machine, feeding mechanism including a transmission shaft, a transmission member thereon, and means for operatively connecting said member and shaft for rotation in the same or opposite directions at equal angular rates, said means including a plurality of friction clutches, a sleeve secured to said shaft and provided with longitudinal grooves, a second sleeve movable longitudinally of said shaft, an annulus for rendering said clutches alternatively operative, and arms connecting said last named sleeve and annulus and guided in the grooves in said first named sleeve. 120
17. In a mining machine, feeding mechanism including a transmission shaft, a transmission member thereon, means including a plurality of coaxially disposed friction clutches for operatively connecting said member and shaft for rotation in the same or opposite directions, and controlling means for said connecting means including a member selectively operable to actuate either clutch but not both simultaneously. 125
18. In a mining machine, feeding mechanism including a transmission shaft, a transmission member thereon, means including a plurality of coaxially disposed friction disc clutches for operatively connecting said member and shaft for rotation in the same or opposite directions, and controlling means for said connecting means including a member extending between said clutches and operative to compress one and release the other. 130

19. In a mining machine, feeding mechanism including a transmission shaft, a transmission member thereon, means for operatively connecting said member and shaft for rotation in the same or opposite directions, and yieldingly actuated controlling means for said connecting means automatically operating upon actuation to cause said connecting means to connect said shaft and transmission member for rotation at equal angular rates irrespective of whether the actuation of said controlling means causes said shaft and member to rotate both in the same direction or the one oppositely to the other.

20. In a mining machine, feeding mechanism including a transmission shaft, a transmission member thereon, means for operatively connecting said member and shaft for rotation in the same or opposite directions, a controlling member for said connecting means, an operating member, and a spring connecting said controlling member and operating member.

21. In a mining machine, feeding mechanism including a transmission shaft, a transmission member thereon, means for operatively connecting said member and shaft for rotation in the same or opposite directions, said means comprising a plurality of friction clutches, a controlling member for rendering said clutches alternatively operative, an operating member, and a spring connecting said controlling member and operating member for movement in a plurality of directions.

22. In a mining machine, feeding mechanism including a transmission shaft, a transmission member thereon, means for operatively connecting said member and shaft for rotation in the same or opposite directions, a longitudinally movable sleeve on said shaft for controlling said connecting means, an operating sleeve on said controlling sleeve, each of said sleeves having a pair of oppositely disposed shoulders arranged respectively adjacent the corresponding shoulders on the other sleeve, a pair of washers each engaging a shoulder on each of said sleeves, and a spring interposed between said washers.

23. In a mining machine, feeding mechanism including a power driven transmission shaft, a transmission member thereon provided with a beveled gear, a second transmission member on said shaft also provided with a beveled gear, one or more beveled pinions connecting said beveled gears, and means for alternatively connecting said transmission members to said shaft for rotation therewith.

24. In a mining machine, feeding mechanism including a transmission shaft, a transmission member thereon provided with a beveled gear, a second transmission member

on said shaft also provided with a beveled gear, a gear casing inclosing said beveled gears, one or more beveled pinions carried in said gear casing and connecting said beveled gears, and means for alternatively connecting said transmission members to said shaft for rotation therewith.

25. In a mining machine, feeding mechanism including a transmission shaft, a transmission member thereon provided with a beveled gear, a second transmission member on said shaft also provided with a beveled gear, a gear casing inclosing said beveled gears and comprising a pair of telescoping shells having registering threaded apertures, screw plugs seated in said apertures and having inwardly projecting studs, beveled pinions journaled on said studs and connecting said transmission members to said shaft for rotation therewith.

26. In a room and pillar mining machine having a frame provided with projecting cutting mechanism and slidably on a mine bottom, a driving motor operatively connected to the cutting mechanism, machine feeding and guiding mechanism including a plurality of flexible feeding portions each having a free extremity connectible to a fixed point during feeding of the machine and extending laterally from opposite ends of the frame, and means driven by said motor for winding in either of said portions including power transmission connections including a plurality of friction clutches selectively operable to reverse the direction of feed, feed controlling mechanism including mechanism for selectively actuating said different clutches, and supplemental clutches for changing the direction and rate of feed located in said power transmission connections at the opposite side of said first mentioned clutches from the motor.

27. A mining machine slidable on a mine bottom comprising a frame, cutting mechanism thereon including a projecting cutter bar disposed longitudinally of said frame and rigidly connected thereto throughout the cutting operations, and a circulating cutter chain on said bar, flexible feeding means and guiding means for said feeding means about which said flexible feeding means may be directed to enable a lateral cut in a face in either direction providing advance and receding portions during lateral cutting in one direction extending laterally in opposite directions from the opposite ends of said frame and having provision whereby said portions may be reversely disposed respectively as receding and advancing portions during lateral cutting in the opposite direction, a motor operatively connected with said cutter chain, and driving connections between said motor and said flexible feeding means including a feed operating

member operatively engaging the latter, and driving connections between the motor and said feed operating member operative to effect operation of said member by said motor
 5 at a plurality of speeds and in opposite directions at each of said speeds having speed change gearing including a plurality of clutches and also having a plurality of selectively operable friction clutches between
 10 said first mentioned clutches and said motor.

28. A mining machine slidable on a mine bottom comprising a frame, cutting mechanism thereon including a projecting cutter bar disposed longitudinally of said frame and rigidly connected thereto throughout the cutting operations, and a circulating cutter chain on said bar, flexible feeding means and guiding means for said feeding means about which said flexible feeding means may be directed to enable a lateral cut in a face in either direction providing advance and receding portions during lateral cutting in one direction extending laterally in opposite directions from the opposite ends 20 of said frame and having provision whereby said portions may be reversely disposed respectively as receding and advancing portions during lateral cutting in the opposite direction, a motor operatively connected 25 with said cutter chain, and driving connections between said motor and said flexible feeding means including a feed operating member operatively engaging the flexible feeding means, and driving connections between the motor and said feed operating member operative to effect operation of said member by said motor at a plurality of speeds and in opposite directions at each of said speeds including speed changing 30 gearing including a plurality of clutches operative when engaged both to change the speed and the direction of rotation of the feed operating member and a plurality of selectively operable friction clutches between said first mentioned clutches and said motor.

29. A mining machine slidable on a mine bottom comprising a frame, cutting mechanism thereon including a projecting cutter bar disposed longitudinally of said frame and rigidly connected thereto throughout the cutting operations, and a circulating cutter chain on said bar, flexible feeding means, and guiding means for said feeding means about which said flexible feeding means may be directed, in order to enable a lateral cut in a face in either direction, to provide advance and receding portions during lateral cutting in one direction extending laterally in opposite direc- 40

tions from the opposite ends of said frame and having provisions whereby said portions may be reversely disposed respectively as receding and advancing portions during lateral cutting in the opposite direction, a motor operatively connected with said cutter chain, and driving connections between said motor and said flexible feeding means including a feed operating member operatively engaging the latter, and driving connections between the motor and said feed operating member operative to effect operation of said member by said motor at a plurality of speeds and in opposite directions at each of said speeds including speed changing 45 gearing including a plurality of clutches between the motor and feed operating member and a plurality of friction clutches selectively operable to reverse the direction of feed and arranged between said first mentioned clutches and said motor.

30. A mining machine slidable on a mine bottom comprising a frame, cutting mechanism thereon including a projecting cutter bar disposed longitudinally of said frame and rigidly connected thereto throughout the cutting operations, and a circulating cutter chain on said bar, flexible feeding means, and guiding means for said feeding means about which said flexible feeding means may be directed, in order to enable a lateral cut in a face in either direction, to provide advance and receding portions during lateral cutting in one direction extending laterally in opposite directions from the opposite ends 50 of said frame and having provision whereby said portions may be reversely disposed respectively as receding and advancing portions during lateral cutting in the opposite direction, a motor operatively connected with said cutter chain, and driving connections between said motor and said flexible feeding means including a feed operating member operatively engaging said flexible feeding means, and driving connections between the motor and said feed operating member operative to effect operation of said member by said motor at a plurality of speeds and in opposite directions at each of said speeds including speed changing 55 gearing including a plurality of clutches operative when engaged both to change the speed and the direction of rotation of the feed operating member and a plurality of friction clutches selectively operable to reverse the direction of feed and arranged between said first mentioned clutches and said motor.

31. In testimony whereof I affix my signature.
 MORRIS P. HOLMES.
